CATAMENIAL BELT

Samuel Rosen, Miami Beach, Fla., assignor of
fifty per cent to Morris J. Berkson, Chicago, Ill.

Application February 16, 1950, Serial No. 144,480

6 Claims. (Cl. 128—291)

1

My invention relates to improvements in sanitary or catamenial belts which serve to support externally worn sanitary absorbent pads or the like conventionally worn during periods of menstrual flow.

Numerous types of sanitary belts have been suggested and marketed. Still commonly employed is one type wherein an elastic band encircles the body of the wearer and, depending from said band, are cloth sections to which the ends of the sanitary pad are attached by means of safety pins or the like. Another type which has more recently come into use is a construction which dispenses with safety pin fastening means but, instead, uses a buckle arrangement. These and numerous other constructions are objectionable for a variety of reasons. Those which employ safety pins very often cause chafing where they contact the skin and the same is true of buckle constructions. Safety pins, moreover, present a hazard due to the possibility of their accidentally opening. Other objections to these and other known constructions are recognized by the wearers but no fully satisfactory catamenial belt has heretofore been evolved.

In accordance with my present invention, a new and materially improved sanitary or catamenial belt has been devised which is exceedingly simple in construction, inexpensive to manufacture and which overcomes the objectionable features which have heretofore characterized sanitary belts, as pointed out above. The sanitary belt of my invention embodies a novel construction wherein the use of pins, buttons, clasps and all metal fastening or attaching means are eliminated.

In general, sanitary belts of the present invention utilize, in combination with a band which is adapted to encircle the wearer, front and back loops of an elastic material in the form of a cord or narrow band or ribbon, the two free ends of each of the loops being attached to the band. It is particularly advantageous to provide front and back of diametrically opposed sections of fabric or the like carried by the band and extending downwardly a short distance therefrom and to attach the free ends of the elastic loops thereto. The loops are adapted to be manipulated by the fingers, in the manner hereafter described, to form releasable knots for firmly securing the ends of an absorbent sanitary pad. The closed end of the loop is provided with a releasing member or tab or tassel whereby, upon pulling said releasing member upwardly, the knot is readily untied. This releasing member, in combination

with the loop arrangement and the other cooperating elements, is an essential part of said novel combination.

Referring, now, to the drawings, wherein a preferred, though illustrative, embodiment of my invention is disclosed;

Fig. 1 is a perspective view of a sanitary belt made in accordance with my invention and showing an absorbent sanitary pad secured in position, the body of the wearer being omitted for purposes of clarity;

Fig. 2 is an enlarged partial perspective view, showing only the front loop member and before the same is manipulated by the fingers to form the knot;

Figs. 3, 4, 5 and 6 show the manner in which the loop is manipulated to secure an end of the sanitary absorbent pad in locked position;

Fig. 7 is a partial perspective view showing the way in which the knot is untied when it is desired to release and remove the sanitary absorbent pad.

As shown more particularly in Figs. 1 and 2, the sanitary belt of my invention comprises a band 10, preferably made of an elastic fabric, and adapted to encircle the waist of the wearer. Carried by the band at the front and rear parts and essentially in diametrically opposed relation to each other are apron sections or loop attaching sections 11 and 12, preferably made of a substantially inelastic fabric. Since the sections 11 and 12 and their associated elements may be and preferably are identical, I shall describe in detail only section 11 which, for convenience, may be referred to as the front section. An elastic cord or narrow ribbon 13 of rubberized fabric or the like is attached to the apron member 11 in any suitable manner. One way which I have found to be quite satisfactory is to form the member 11 of at least two layers of fabric, for example, of nylon, rayon, cotton or the like, and sew the free ends 14 and 16 of the elastic cord or ribbon between the fabric layers by rows of stitching 17. The layers comprising member 11 may be stitched together at their edges as shown at 18, and member 11 may be attached to band 10 by stitching. Any other means of attaching the parts may be utilized as, for example, by fusion where thermoplastic materials are utilized. At the bottom of the closed loop formed by cord or ribbon 13, I provide a releasing member or tab or tassel 19, preferably formed of a fabric such as nylon, rayon, or the like.

Referring, now, to Figs. 3 to 6, inclusive, with the band 10 encircling the waist of the wearer and

the apron members 11 and 12 in front and rear positions, the loop is spread, preferably between the thumb and first finger as shown in Fig. 3, to provide a lower strand 21 and upwardly converging strands 22 and 23. Thereupon, the diverging strands are bent over the strand 21 whereby to form two individual loops, one, 24, encircling the thumb, and the other, 26, encircling the first finger. The loops 24 and 26 are then disposed in superposed relation to each other and the thumb and first finger slipped out, an end 27 of the sanitary absorbent pad 28 is inserted through the superposed loops 24 and 26, and the strands 22 and 23, now in more or less vertical relation, are pulled upwards. This serves to form a knot which very firmly holds the pad end 27 against movement. The opposite or rear loop may then be operated in like manner to tie or knot the other end 29 of the sanitary absorbent pad. This latter operation or manipulation may be done with the rear loop in rearward position. If this should, in any case, prove cumbersome, then the following alternative procedure may be followed. After the pad end 27 has been tied in front as described above, the waist band 10 may be swung around so that the previous rear portion is in front. The sanitary pad is then passed between the legs from the rear to the front and the other loop then manipulated as described from the front.

When it is desired to remove or replace the sanitary pad, this is readily achieved simply by pulling upwardly on each of the releasing members 19, as shown in Fig. 7, whereupon the knot is untied to permit the ends of the pads to be withdrawn.

It will be seen, in the light of the foregoing description, that I have devised an exceedingly simple and inexpensive sanitary belt, which is safe to use, and which overcomes various of the objectionable features which have characterized previously known and used constructions. Sanitary belts made in accordance with my invention may be and most advantageously are made so as to be free of any metal parts. They are advantageously made of cotton, rayon, nylon or similar textile materials which may be washed and dried with a minimum expenditure of effort and time.

While the invention has been described in the form of a particularly preferred embodiment, it should be understood that said description is by way of illustration and is not limitative of the full scope of the invention since various of the details may be slightly modified without departing from the essential teachings contained herein.

What I claim as new and desire to secure by Letters Patent of the United States is:

1. In a sanitary belt of the type which includes a band adapted to encircle the waist of the wearer, the improvement which comprises front and rear apron members carried by said band and extending downwardly a short distance therefrom, a loop of elastic cord or the like extending downwardly from each of said apron members, each of said elastic cord loops being adapted to be manipulated by the fingers to form a releasable knot for firmly securing the ends of an absorbent sanitary pad, and a releasing member attached to the bottom of each of said elastic cord loops whereby, upon pulling said releasing member upwardly, the knot in said elastic loop is untied.

2. In a sanitary belt of the type which includes a band adapted to encircle the waist of the wear-

er, the improvement which comprises front and rear substantially inelastic sections of fabric or the like carried by said band and extending downwardly a short distance therefrom, a loop of elastic cord or the like extending downwardly from each of said inelastic sections, each of said elastic loops being adapted to be manipulated by the fingers to form a releasable knot for firmly securing the ends of an absorbent sanitary pad, and a releasing member attached to the bottom of each of said elastic loops whereby, upon pulling said releasing member upwardly, the knot in said elastic loop is untied.

3. In a sanitary belt of the type which includes an elastic band adapted to encircle the waist of the wearer, the improvement which comprises diametrically opposed substantially inelastic sections of fabric or the like carried by said band and extending downwardly a short distance therefrom, a loop of elastic cord or the like extending downwardly from each of said inelastic sections, each of said elastic loops being adapted to be manipulated by the fingers to form a releasable knot for firmly securing the ends of an absorbent sanitary pad, and a releasing fabric member attached to the bottom of each of said elastic loops whereby, upon pulling said releasing member upwardly, the knot in said elastic loop is untied.

4. In a sanitary belt of the type which includes an elastic band adapted to encircle the waist of the wearer, the improvement which comprises front and rear substantially inelastic sections of fabric or the like carried by said band and extending downwardly a short distance therefrom, a loop of elastic cord or the like extending downwardly from each of said inelastic sections, each of said elastic loops being adapted to be manipulated by the fingers to form a releasable knot for firmly securing the ends of an absorbent sanitary pad, and a releasing fabric member attached to the bottom of each of said elastic loops whereby, upon pulling said releasing member upwardly, the knot in said elastic loop is untied.

5. In a sanitary belt of the type which includes a band adapted to encircle the waist of the wearer, the improvement which comprises front and rear loops of elastic cord or the like extending downwardly from the band, each of said elastic cord loops being adapted to be manipulated by the fingers to form a releasable knot for firmly securing the ends of an absorbent sanitary pad, and a releasing member attached to the bottom of each of said elastic cord loops whereby, upon pulling said releasing member upwardly, the knot in said elastic loop is untied.

6. In a sanitary belt of the type which includes an elastic band adapted to encircle the waist of the wearer, the improvement which comprises front and rear loops of elastic cord or the like extending downwardly from said band, each of said elastic loops being adapted to be manipulated by the fingers to form two superposed closed loop sections which, in turn, are formed into a releasable knot for firmly securing the ends of an absorbent sanitary pad, and a releasing fabric member attached to the bottom of each of said elastic loops whereby, upon pulling said releasing member upwardly, the knot in said elastic loop is untied.
